REVERSIBLE CYCLE SYSTEM

Gert K. A. Siggelin, Falls Church, Va., assignor to Desomatic Products, Inc., Falls Church, Va., a corporation of Delaware

Application November 25, 1955, Serial No. 549,213

20 Claims. (Cl. 62—81)

This invention relates to an improved reversible fluid flow thermodynamic cycle and apparatus operating with such for removal of vapors from gases including dehumidification and other practical applications of such cycle.

This invention further provides an improved devaporizing of gases in a reversible fluid flow thermodynamic cycle wherein vapor removal from gases is effected by refrigeration of the gas in contact with refrigerated coils, wherein the refrigerant passing through separate coils, such as the evaporator and condenser of a compressed gas refrigerating cycle, as well as gas flowing serially in contact with these coils are both periodically reversed for improved devaporizing and enhanced thermodynamic efficiency of the refrigeration cycle.

The invention further provides enhanced control for optimum dehumidification of gases with variably volume, sensible heat and moisture contents.

In one aspect of this invention the gases may be efficiently devaporized. For instance, air may be dehumidified to dew points below 32° F. or even below 0° F., as desired by periodically reversing the gas flow in sequence, first over a cold refrigerant evaporator coil and then over a relatively warm condenser coil efficiently to deposit its moisture upon the cold evaporator coils. Periodically when the heat transfer efficiency tends to be reduced by an ice coating forming upon the refrigerating coil, such solid phase ice deposits reducing the heat transfer efficiency, the refrigeration cycle, as well as the gas flow direction, is reversed. The evaporator and condenser coils are converted from one function to the other interchangeably whereby the warm condenser on reversal of refrigerant flow is made the cold evaporator in the refrigeration cycle, and the cold ice covered evaporator becomes the condenser. The direction of gas flow over these coils is simultaneously reversed with gas flow over these coils is simultaneously reversed with the refrigeration cycle so that the gas then becomes cooled first in contact with an ice free cold coil and the now heated warm condenser coil has its ice film rapidly melted. One result of this cycle is a continuous and efficient heat exchange first to cool the gas to deposit moisture on the cold evaporating coil and thereby effecting dehumidification to a dew point close to the temperature of that cold coil, without interference of an ice deposit, thereby producing an unusually low dew point in the gas. Then passing the cold dehumidified gas over the warm condensing coil of the refrigerating system the gas becomes reheated to normal temperature, but remains very dry gas of even lower relative humidity, while most efficiently cooling the condenser of the refrigerating system to enhance the efficiency of that system.

Thus this system is a controllably reversed refrigerating system comprising both a condensing and an evaporating coil and a controllably reversed gas cycle passed in sequence over these coils for highly efficient dehumidification to any desired low dew point while simultaneous-

2

ly enhancing the refrigeration system efficiency. For further improvement in efficiency of the system, the fan, reversible with the refrigeration system, may be operated at controlled speeds responsive to desired temperatures or vapor content of the gas passed over the coils. For example, a gas of high moisture content or high sensible heat is desirably passed more slowly over the coils than gas under opposite conditions.

There are other practical applications of this system besides efficient devaporization of gases and enhanced efficiency of a refrigerant cycle. For instance, while it may be desirable to dehumidify a gas to a dew point below such as is practically available under present systems, it is also desirable in air conditioning systems to reheat the cold dehumidified gas to a comfortable temperature thereby greatly reducing its relative humidity.

In another aspect where vapors are desirably removed from a gas such as in a natural gasoline recovery system from petroleum gases, that natural gasoline may be removed by passing the wet gas in contact with refrigeration coils to condense the liquids carried thereby upon the evaporator coil for recovery thereof. However, the gas itself becomes cooled, oftentimes to an undesirably low temperature, resulting in loss of gas pressure on the system and the passage of the devaporized cold gas in contact with the warm condensing coil of the refrigerating system warms and restores the sensible heat of the gas, thereby increasing its pressure to substantially the original pressure of the system thereby maintaining the system at a substantially constant pressure and obviating distribution problems in gas flow.

The present system, moreover, allowing passage of gases at a controlled rate over evaporating and condensing coils in series may be controlled to such rate as not only enhances the efficiency of the refrigerating system but also may correspond to a rate adjusted to maximum efficiency to remove the vapor content of such gases to a maximum degree. For instance the timing of the reversal of cycles may be controlled by the ice deposit on the evaporator coil as well as other desirably controlled variables of the system, or it may be simply set for periodic reversal regularly with passage of a certain time period.

The system will be further explained in conjunction with the drawings appended hereto wherein:

Fig. 1 illustrates diagrammatically the complete system; and

Fig. 2 is an overall wiring diagram for such system.

Referring to Fig. 1, a refrigerant gas such as "Freon" is compressed in compressor 10 of conventional refrigerant compressor construction to a pressure sufficient to liquify that gas when cooled below its critical temperature and passed under such pressure through a line 12 to a 4-way valve 14 and thence by way of line 16 to a condenser coil 18. That condenser coil may be any conventional refrigerant heat exchanger designed for cooling of the refrigerant gas in contact with a cold gas that has been dehumidified. For example, it may be of conventional fin coil or other known heat exchanger construction.

The hot compressed gas becomes condensed in coil 18 to a liquid refrigerant under the relatively high pressure of the compressor 10 and passes through line 20 by check valve 22 in line 24 to receiver 26. It passes from receiver 26 through a conventional thermo expansion valve 28 as controlled by a remote control bulb 30 sensitive to the degree of super heat contained in low pressure refrigerant gas. The gaseous and liquid Freon from thermo expansion valve 28 pass through line 32 by way of check valve 34 and thence into the evaporator coil 36 where it is evaporated to a gas and de-

velops lowest refrigerating temperature well below 30° F. and often as low as -30° F.

The low pressure cold gas from evaporating coil 36 is returned to the low pressure side of 4-way valve 14 by way of line 38 and thence returned to the suction side of the compressors by way of line 40. As shown a conventional sensing bulb 30 responsive to the temperature of the gas in line 40 is set to control the thermo expansion valve 28 at about 5° of superheat in the return gas.

A gas lead duct 42 is taken from line 12 to bleed a small quantity of refrigerant gas under high pressure and serves to actuate the 4-way valve through a conventional diaphragm valve control 49 which actuates arm 44 thereby moving the 4-way valve by pneumatic pressure for reversing the direction of flow between ducts 16 and 38. After actuation to reverse the valve 14, gas in line 42 is returned by way of line 46 to the low pressure line 40. While the actual reversal of the vane position of 4-way valve 14 is effected by the gas pressure produced in compressor 10 through lines 12 and 42, the actual operation of the valve reversal mechanism is triggered by a small solenoid actuated pilot valve 48 (Fig. 2) which directs the flow of gas to the diaphragm control 49. The solenoid controlled gas pressure actuated valve control 49 for a multiway valve is of known construction and accordingly is shown here only diagrammatically.

When the refrigerant flow in the refrigerating system is reversed, as triggered by the solenoid pilot valve 48, gas pressure in line 42 actuates arm 44 and reverses 4-way valve 14 to its dotted line position. In that position compressed gas in line 12 passes first by way of duct 38 to coil 36, which now becomes a reheating or condenser coil, and the condensed compressed gas therein then passes through line 32 into line 24 protected by check valve 50 and again passes to receiver 26. From receiver 26 the refrigerant passes out through thermo expansion valve 28 and into line 20 protected by check valve 52, and thence into evaporating (cooling) coil 18 from which it finally returns to 4-way valve 14 by way of line 16 and thence to the suction side of the compressor 10, again by way of line 40.

As shown in the full line position of the apparatus of Fig. 1, the coil 36 is the evaporator coil and produces the lowest temperature while coil 18 is the condenser coil and will be heated by the condensation of the condensing refrigerant. Both coils are mounted within a gas duct 59 through which gas passes in the direction of the full line arrows. That gas, passing first over the cold evaporator coil 36, is cooled to below its dew point and deposits its condensed vapor content on the surface of coil 36 as liquid. The cold gas then passes onward in contact with coil 18 which, relatively warm, reheats the gas such as air to approximately the same temperature as it originally was before cooling. The reheated gas then passes out of duct 59 as reheated gas of even lower relative humidity. A reversible fan 60 is mounted preferably, but not essentially, between the coils, inducing flow over the cooling coil and forcing flow over the heating coil. Liquid as deposited moisture accumulating on coil 36 drips off the coil into a sump or pan 61 to receive the accumulated liquids at the bottom of the cold coil, from which the liquid may be continuously or periodically drained through duct 63, controlled by a valve 65. When solid phase liquid such as ice begins to accumulate on the cold coil 36, the flow of gas over both coils is reversed by reversing the fan 60, while simultaneously reversing the refrigerant flow as described. Coil 18 therefore then becomes the cold evaporator coil of the refrigeration system and coil 36 becomes the hot condenser coil thereof. This reversal of the fan then causes the air to flow in reverse direction as shown by the dotted line arrows and a similar sump or pan 67 mounted below coil 18 receives de-

posited liquid drained from coil 18 and this liquid is withdrawn therefrom through duct 69 continuously or intermittently as controlled by valve 71.

Fan 60 is operated at a speed either coordinated for continuous speed variation with the vapor content or temperature characteristics of the gas passing through duct 59, or that speed control, on the same principles will be set at two or three alternate practical speeds for the particular gas characteristics. By this variation, for example, a gas with a high sensible heat or a gas with a high vapor content may be passed more slowly over the cooling and reheating coils than one which is already at approximately its dew point or one which may have little moisture content to deposit, or even one wherein extreme dew point lowering is not necessary, and therefore the gas could be flowed over the coils at greater speed. Since the deposited moisture is continuously or intermittently removed from the system, and the cycle is reversed as soon as the accumulation of solid phase liquid or ice upon the cooling coil (evaporator) takes place, or as soon as heat exchange by ice accumulation has been reduced to a selected value, the practical temperature of the gas cooled by the cooling coil may be almost as low as the temperature of the coil itself because of the efficient heat exchange in the absence of ice or at some practically fixed limit for dehumidification efficiency. For these reasons the dew point of the gas may be reduced as desired to a temperature far below that of ordinary dehumidifying systems wherein the dew point of the gas cannot be reduced below the temperature of ice or solid phase liquid upon the cooling coil. Upon reversal of the refrigerant flow there is momentary, but practically very little lag in readjustment of temperatures of the respective coils.

Moreover, it will be appreciated that a cold gas chilled in contact with the cooling (evaporator) coil becomes more highly efficient to cool the condenser coil over which it passes in reheat thereof. This makes the refrigeration system per se more efficient. Finally, following the known practice in the art, the remote bulb 30 is set for about 5° of superheat in normal operation of the refrigeration system so that the cooling produced by the rate of gas expansion is not only at an optimum but is controllable thereby to produce any desired temperature in the cooling coil.

Fig. 2 shows an electrical hookup for the system, including a reversible fan with control elements for varying the fan speed to accommodate variable temperature air flows and with means controlled by a timer circuit for reversing the flow of air over the respective coils. The speed of the fan motor may be controlled for continuous variation by varying the resistivity and thereby the current passing to the fan motor, continuously varying with the temperature sensed in the air stream by a sensing bulb. However, for most practical purposes the fan motor may be controlled at two different selected speeds for operation at either, and at temperatures alternately in either of two practically selected temperature ranges.

As shown in Fig. 2 the fan 60 (Fig. 1) is mounted for drive on the armature of reversible fan motor 62. The fan motor derives electrical power as a single phase motor from two lines 64 and 66 of a three phase current supply including a third line 68 thereof used for powering a three phase compressor motor 70. One electrical lead 72 is connected to a contact pole 74 of a temperature sensitive snap acting switch arm 76 which feeds the current to respective current contact leads 78 and 80 for either of two speed current supply. These leads 78 and 80 connect with respective coil windings of either of the two speed wound single phase fan motor 62. The switch arm 76 comprises a micro switch of standard construction which, as shown diagrammatically, is actuated by an arm 82 connected to a diaphragm 84 whose position is variable responsive to fluid pressure above the dia-

phragm exerted by fluid in a sensing bulb 86 exposed to the gas such as moved by the fan 60, and the fluid of the sensing bulb is connected to the top of the diaphragm space through a capillary tube 88 for transfer of fluid pressure to the diaphragm 84. The other circuit lead 90 completes the current flow to the motor 62.

The motor 62 in known construction has a reversing coil (not shown) which determines the direction of rotation of the armature as controlled by the polarity of a capacitor 92 in circuit by way of lead 94 with one end of said coil and 96 at the other. A lead 98 taken from line 78 passes polarizing current through a switch arm 100 to direct current to either of leads 94 and 96 by way of alternate switch contacts 102 and 104. Similarly a lead 106 connected to line 90 passes current through switch arm 108 alternately to both of these lines 94 and 96 through leads 110 and 112. Both switch arms 100 and 108 are held together by an arm 114 forming a part of or connected to an armature of a solenoid having a coil 116. Coil 116 is energized by leads 118 and 120 carrying current from lines 122 and 124 which simultaneously energize a second solenoid of pilot valve 48, lines 122 and 124 being directly connected to the power input circuit lines 64 and 66. A timer motor 126 is energized by leads 128 and 130 connected respectively to power inlet leads 90 and 72. The timer motor which may be a small electric motor continuously rotating and geared to a selected slow rate actuates by its armature through a cam driven contact switch arm 132 in line 122 makes and breaks the circuit therein according to a predetermined time period.

When the switch arm 132 is closed by timer motor 126 to complete the circuit in line 122, the solenoid pilot valve 48 is energized to reverse the position of the 4-way valve 14, as explained above, and simultaneously energizes coil 116 thereby moving the solenoid armature and its arm 114 to lower both switch arms 100 and 108 to dotted line position, thereby reversing the polarity of capacitor 92 and simultaneously thereby reverses the direction of fan motor 62.

The speed control of the fan in either direction is relatively independent of the direction control of that motor 62 whereby switch arm 76 will be moved to high or low speed (dotted line) positions as controlled independently by sensing bulb 86 responsive to the temperature of the air-flow.

While the temperature control circuit as shown is for alternate speeds high and low, preselected, the speed variation circuit may be continuously variable with the temperature and for that purpose instead of the snap acting switch 76 arrangement as shown, a variable resistor may be substituted to merely vary the current to the fan by temperature or other continuous control element for purposes of varying the fan speed.

Similarly, while a timer comprising the electrical motor 126 is shown to give, by a continuous rotary drive, a periodic measurement of time, the solenoid 116 may be made responsive to other control factors in the cycle to obtain reversibility of the fan motor at a critical point of the cycle. For instance, instead of the control motor 126 as measuring a continuous time period, a control such as the resistivity of an ice layer deposited upon the evaporator coil 36 of the refrigeration system may be used, whereby after a layer of a certain thickness or resistivity or heat transfer differential results, that critical value may be used as electrical control upon switch 132 to effect reversal of both refrigerant flow by solenoid 48 as well as fan motor 62.

The refrigerant gas compressor motor 70 is preferably a three-phase motor actuated by a master switch 134 passing current to each of lines 64, 66 and 68 which may be conventionally protected by fuses 136. The three-phase motor 70 is protected by a conventional overload circuit comprising resistors 138 in each of two of the three lines,

each resistor cooperating with a normally closed switch 146 to open the same when overloading current, developing an excessive temperature in resistors 138, is present. In order to make the compressor circuit independent of the fan circuit, thereby allowing the compressor power to be cut off while allowing the fan motor to continue, an additional switch 142 is placed in the circuit which is protected by a starting coil 144 and condensers 140 which in turn energizes the three switches 146 to closed position. The entire compressor circuit portion enclosed within the dotted line box is merely a conventional starter circuit for a heavy duty compressor motor with overload protection. While as shown the compressor motor for heavy duty is of three phase type, for smaller installations an ordinary single-phase compressor motor may be substituted.

As thus described, an improved thermodynamic cycle is provided having improved utility for several purposes. For example, inasmuch as vapor containing gases are cooled to approximately the temperature of the evaporator coil of the refrigeration system without substantial reduction of heat transfer by ice coating, the dew point of such gas may be reduced to approximately the temperature of the evaporator coil and, as desired, to an extremely low dew point as described. Intermediate dew points, of course, can be obtained by allowing an ice or solid phase coating to develop upon the refrigerating coil in which event the dew point will vary with the heat transfer up to the dew point at the melting point of the ice. Such intermediate can also be obtained by operating under other conditions of reduced heat transfer such as by passage of gas over the evaporator coil at higher rates.

In a further advantage of such system the relative humidity of a low dew point gas is greatly decreased by reheat of the gas.

As another advantageous use of the present system, the refrigerant cycle is substantially increased in efficiency by the cold gas produced in contact with the evaporator coil to use that cold gas as a more efficient cooling medium for the condensing coil.

As a further improvement in the art, the system herein described provides for flow of gas correlated with a particular refrigerant system to flow the gas for dehumidification and reheating at a rate for optimum refrigeration efficiency as well as for optimum dehumidification efficiency so that the system is flexible to handle gases of variable moisture as well as the sensible heat contents.

Certain modifications will occur to those skilled in the art and such variations of the system as are known for dehumidification of gases, for air conditioning and for operation and construction of refrigeration systems comprising gas compression and expansion may be used herein. It is accordingly intended that the description given herein be regarded as exemplary and not limiting except as defined in the claims appended hereto.

I claim:

1. A reversible thermodynamic cycle system comprising a refrigeration apparatus including a refrigerant gas compressor, a refrigerant condenser, a refrigerant evaporator, and duct means interconnecting said refrigeration apparatus elements to pass refrigerant from the compressor to the condenser and then to the evaporator, means for passing a gas first in heat exchange contact with said evaporator and then in heat exchange contact with said condenser, means for reversing the cycle of refrigerant flow whereby the evaporator becomes the condenser and the condenser the evaporator of the refrigeration system, and means for reversing the flow of gas in heat exchange contact with said evaporator and condenser.

2. A reversible cycle gas devaporizing system comprising an evaporator and a condenser, a refrigerant gas compressor and means for passing refrigerant first to the condenser and then to the evaporator, means for passing

gas to be devaporized first in heat exchange contact with said evaporator to be cooled and deposit liquified vapors thereon and then in heat exchange contact with said condenser for reheating the cooled devaporized gas, means for reversing the flow of refrigerant in the refrigerant cycle whereby the condenser becomes the evaporator and the evaporator the condenser, means for reversing flow of gas to be devaporized for continued heat exchange contact first with the evaporator and then with the condenser and means for removing liquified vapors deposited on said evaporator in both directions of gas flow.

3. A reversible thermodynamic cycle apparatus comprising two independent heat exchangers, a refrigerant compressor adapted to compress refrigerant gas and means to pass compressed refrigerant gas first to one heat exchanger as a condenser and then to the other as an evaporator, a multiway valve comprising means to reverse the flow of refrigerant from said compressor whereby the function of the heat exchangers is reversed and the evaporator then functions as a condenser and the condenser then functions as an evaporator, means to pass a gas in heat exchange relationship to both of said heat exchangers in series first to the cold heat exchanger comprising the evaporator to become cooled and then to the warm heat exchanger comprising the condenser to become reheated, and means coupled with said refrigerant flow reversing means for reversing the flow of gas in heat exchange contact with said heat exchangers.

4. Apparatus as defined in claim 3 wherein the means to pass gas over said heat exchangers in series is a fan having a reversible motor adapted to rotate said fan in reverse with the reversal of said refrigerant cycle.

5. Apparatus as defined in claim 3 wherein the means to pass gas over said heat exchangers in series is a fan having a reversible motor, and means for varying the speed of said motor in both directions of rotation.

6. Apparatus as defined in claim 3 wherein the means to pass gas over said heat exchangers in series is a fan having a reversible motor, and means for varying the speed of said fan between an approximately fixed high speed and an approximately fixed lower speed in both directions of rotation.

7. Apparatus as defined in claim 3 wherein the means to pass gas over said heat exchangers in series is a fan having a reversible motor, and means for varying the speed of said motor in both directions of rotation, said means for varying the speed of rotation being responsive to the sensible temperature of the influent gas passed in contact with said heat exchangers.

8. A reversible thermodynamic cycle apparatus comprising two independent heat exchangers, a refrigerant compressor, means to pass compressed refrigerant in sequence first to one heat exchanger as a condenser and then to the other as an evaporator, and means to reverse the sequence of flow of refrigerant from said compressor to said heat exchangers whereby the function of each heat exchanger is reversed and the evaporator upon flow reversal then functions as a condenser and the condenser then functions as an evaporator, a motor driven fan mounted in said apparatus to pass a gas in heat exchange relationship to both of said heat exchangers in series first to the cold heat exchanger functioning as an evaporator whereby the gas becomes cooled and then to the warm heat exchanger functioning as a condenser whereby the cooled gas is reheated, means coupled with said refrigerant flow reversing means for reversing the fan motor and thereby the direction of flow of gas in heat exchange contact with said heat exchangers, and a timer in circuit with said reversible motor and refrigerant flow reversing means for periodically effecting reversal of both.

9. A reversible thermodynamic cycle apparatus comprising two independent heat exchangers, a refrigerant compressor, means to pass compressed refrigerant from said compressor in series first to one heat exchanger as a

condenser and then to the other as an evaporator, and a 4-way valve mounted to reverse the sequence of flow of refrigerant from said compressor to both of said heat exchangers whereby the function of each heat exchanger is reversed and the evaporator upon flow reversal then functions as a condenser and the condenser then functions as an evaporator, said heat exchangers being mounted within a gas conveying duct, an electric motor driven fan in said duct to pass a gas in heat exchange relationship to both of said heat exchangers in series first to the cold heat exchanger functioning as an evaporator whereby the gas becomes cooled and then to the warm heat exchanger functioning as a condenser whereby the cooled gas is reheated, a solenoid mounted to actuate said 4-way valve to effect refrigerant flow reversal, means for reversing the direction of drive of said fan motor whereby the direction of flow of gas in heat exchange contact with said heat exchangers is reversed, electric circuit means coupling said 4-way valve actuating solenoid and said fan motor in both directions of rotation having means for reversing the direction of rotation of said fan motor, and a timer in said circuit adapted to periodically effect reversal simultaneously of said fan motor and the 4-way valve setting.

10. Apparatus as defined in claim 9 wherein the fan motor is rotatable at variable speeds and means in said circuit responsive to ambient temperature before heat exchange of gas passing in said duct to vary the speed of said fan motor.

11. In an improved thermodynamic cycle the steps comprising compressing a refrigerant gas, serially condensing said refrigerant gas in a heat exchanger whereby heat is evolved and then evaporating the condensed gas in a second heat exchanger whereby heat is absorbed to produce cooling, passing an extraneous gas serially first in heat exchange contact with the gas being evaporated to cool the extraneous gas and then in contact with the first heat exchanger to reheat the extraneous gas, periodically reversing the cycle of refrigerant flow to pass compressed gas to the heat exchanger that was the cold evaporator to condense the refrigerant therein and to evolve heat, passing the condensed refrigerant then to the heat exchanger that was the condenser to evaporate the same absorbing heat and producing cooling, and simultaneously reversing the flow of extraneous gas over said heat exchangers in series with the reversal of refrigerant flow therein.

12. The method of devaporizing a gas comprising passing the gas in heat exchange contact with the cold evaporator of a compressor-expander refrigeration system to cool said gas and deposit liquified vapor on said evaporator and thereby effect devaporizing of said gas, then serially passing the cold devaporized gas in heat exchange contact with the hot condenser of said compressor-expander system, whereby the devaporized gas is reheated, reversing the cycle of said compressor-expander refrigeration system whereby the condenser becomes the evaporator and the evaporator the condenser and simultaneously reversing the flow of gas to be devaporized in heat exchange contact with said refrigerant system, whereby the gas to be dehumidified continues to pass serially in heat exchange contact with an evaporator and condenser of said system, and removing liquified vapors deposited on the cold evaporators.

13. The method as defined in claim 12 wherein the gas to be dehumidified is air and the moisture deposited in contact with each refrigeration element functioning as the evaporator is withdrawn from the system.

14. The method as defined in claim 12 wherein the reversal of the cycle is timed to take place when the heat exchange upon the evaporator coil is substantially reduced.

15. The method as defined in claim 12 wherein the reversal of the cycle is periodically timed to avoid reduction of heat exchange of the gas to be devaporized

in contact with the evaporator element by solid phase liquid formation.

16. The method as defined in claim 11 wherein the volume of gas passed in contact with the evaporator and condenser elements is varied with the ambient temperature of the gas.

17. The method of reducing the dew point of a gas below 32° F. by refrigeration dehumidification comprising passing the gas in contact with the evaporator coil of a compressor-expander refrigeration system while maintaining the temperature of said evaporator coil at a temperature below 32° F., and then reheating the dehumidified gas by passing the same in contact with the condenser coil of said refrigeration system while removing condensed liquid phase moisture deposited upon said cold evaporator coil, whereby solid phase moisture tends to form upon said cold evaporator coils and reduce heat exchange with the gas being cooled thereover, periodically reversing the cycle of refrigerant flow between the condenser and the evaporator coils to make the condenser the evaporator and the evaporator the condenser, and simultaneously reversing the flow of air to be dehumidified whereby cooling for dehumidification of said air is effected upon an ice free evaporator coil while the ice deposited upon the condenser coil, which was formerly 25 deposited upon the evaporator coil before reversal, becomes melted by the heat produced in said coil upon reversal.

18. The method as defined in claim 17 wherein the gas to be dehumidified is passed over said coils at a rate variable with its sensible heat content.

20

25

30

53,017

19. The method as defined in claim 12 wherein the extraneous gas is passed in heat exchange with the gas being evaporated at a rate variable with its ambient temperature.

5 20. A reversing thermo-dynamic system comprising a refrigeration system including two heat exchangers adapted to act alternately as a condenser and an evaporator in serial flow of refrigerant therethrough and a reversing means in the refrigerant cycle to reverse the sequence 10 of flow of refrigerant through said heat exchangers, means for passing a gas serially in heat exchange contact with both of said heat exchangers reversible to pass said gas in serial contact with said heat exchangers in either sequence, and timing means interconnected with both refrigerant and gas flow means to periodically and simultaneously reverse the direction of flow of both refrigerant and gas flows.
